(57) CLAIM

(21) Appl. No.: 29/181,142

The ornamental design for a lawn mower grass catcher bag with zipper side-opening, as shown and described.

(22) Filed: May 6, 2003

DESCRIPTION

(51) LOC (7) Cl. 15-03

FIG. 1 is a perspective view of a lawn mower grass catcher bag with zipper side-opening, showing my new design from the front, top, and right side, the left side being a mirror image thereof with the zipper side-opening omitted;

(52) U.S. Cl. D21/17

FIG. 2 is a front elevation view thereof;
FIG. 3 is a rear elevation view thereof; and,
FIG. 4 is a right side elevation view thereof, the left side being a mirror image thereof with the zipper side-opening omitted.
